(57) **CLAIM**

The ornamental design for a display assembly, as shown and described.

DESCRIPTION

FIG. 1 is a perspective view of a display assembly, showing the display assembly in a resting position and showing our new Design in accordance with a first variant of said Design;

FIG. 2 is a front view of the display assembly shown in FIG. 1;

FIG. 3 is a rear view of the display assembly shown in FIG. 1;

FIG. 4 is a left-side view of the display assembly shown in FIG. 1;

FIG. 5 is a right-side view of the display assembly shown in FIG. 1;

FIG. 6 is a top plan view of the display assembly shown in FIG. 1;

FIG. 7 is a bottom plan view of the display assembly shown in FIG. 1;

FIG. 8 is a perspective view of the display assembly shown in FIG. 1, in which the display assembly is in a raised position;

FIG. 9 is a perspective view of a display assembly, showing the display assembly in a resting position and showing our new Design in accordance with a second variant of said Design;

FIG. 10 is a front view of the display assembly shown in FIG. 9;

FIG. 11 is a rear view of the display assembly shown in FIG. 9;

FIG. 12 is a left-side view of the display assembly shown in FIG. 9;

FIG. 13 is a right-side view of the display assembly shown in FIG. 9;

FIG. 14 is a top plan view of the display assembly shown in FIG. 9;

FIG. 15 is a bottom plan view of the display assembly shown in FIG. 9; and,

FIG. 16 is a perspective view of the display assembly shown in FIG. 9, in which the display assembly is in a raised position.

The broken lines shown in the Figures represent portions of the display assembly that are unclaimed environment, boundaries, contour lines, fold lines, or a combination thereof only, that form no part of the claimed design. All surfaces not shown form no part of the claimed design. The shade lines in the Figures show contour and not surface ornamentation. The oblique line shading in the Figures shows a transparent surface and not surface ornamentation.

(Continued)

The appearance of any portion of the display assembly between break lines forms no part of the claimed design.
